UNITED STATES PATENT OFFICE

2,160,658

CLOTHESPIN BAG

Carl S. Hedquist, Minneapolis, Minn.

Application March 4, 1937, Serial No. 128,979

3 Claims. (Cl. 248—99)

My invention relates to an article best designated as a clothespin bag although its usefulness is of broader scope than such designation would indicate, for example, with slight modification, the device is useful for suspension of a cloth sack such as used by a housewife in the process of making jelly from fruits and berries.

The usefulness and convenience of this device will be readily understood from the following description.

The main object of my invention is to provide a simple, highly efficient and inexpensive bag suspending device of unique construction as herein set forth and illustrated in the accompanying drawing, in which:

Fig. 1 is an elevation of my improved device in the form of a clothespin bag suspended from a clothesline. Fig. 2 is a rear view, in enlarged scale, of Fig. 1, the bag being omitted. Fig. 3 is a rear view of the hanger joint part of my device and which connects the vertical stem and the loop members of the device. Fig. 4 is an interior view of the front channel part of the joint member. Fig. 5 is a side or edge view of Fig. 3 as seen from the left, the two channel members of the joint being shown spread apart downwardly. Fig. 6 is a top end view of Fig. 3. Fig. 7 is the lower part of Fig. 3 modified to show the loop member in a certain position other than shown in Figs. 1 and 2. Fig. 8 is a lower end elevation of the joint device and Fig. 9 is an interior elevation of the smaller channel member of the joint which normally lies parallel to and longitudinally within the other and larger channel member of the joint.

Referring to the drawing by reference numerals, like characters being used throughout the various views to designate corresponding parts:

My device comprises an upper hanger or handle member, an intermediate joint member at the lower end of said handle, a loop member pivotally and removably retained in the joint member and a bag member suspended from said loop, the first three members all of metal and the bag member preferably of woven material. Said joint member comprises the most important feature of the device, embodying easily adjusted means for holding the open end of the bag (by means of the loop member) selectively in three desirable and necessary positions.

For convenience of description I will describe the upper, intermediate and lower sections of the device in that order and their useful combination will be most readily understood.

55 10 designates a single piece wire hanger, com-

prising the handle of my device, formed with a simple coil or loop 10A from which two arms of it extend upwardly and diverging, as 10B, to a predetermined height thence both bent forwardly and thence downwardly in approximately parallel relation, as 10C, forming an inverted hook, said parallel arms extending downwardly and their lower extremities bent toward each other as at 10D (Fig. 4) and said upper hook shaped part comprising means for hanging the device 10 as on a clothesline 11. Thus is formed the upper section of my device and hereinafter designated the handle.

The intermediate or joint member of the device, of metal, comprises certain new and unique means for removably and adjustably retaining the loop member 12 in selective positions, namely in a plane at right angles to the handle or parallel to the handle. This joint member is most clearly illustrated in Figs. 3-9 inclusive.

The lower metallic member of the device comprises a simple wire loop 12 which may be ovate or circular, the adjacent free ends of this loop bent outward to provide two short fingers 12A normally parallel to each other.

The bag of the device is preferably a good grade of woven material and for each hanger I prefer to provide two forms of bags, one of the usual elongated quadrangular type, as 13 in Fig. 1. In either type of bag its upper open end is 30 hemstitched as at 13B making said upper end a continuous tube, slitted transversely at one place, as 13C, in Fig. 1, to permit insertion of the wire loop 12 so that only the finger parts 12A of said loop are exposed for the purpose of inserting the 35 finger parts in the joint member and retaining the loop in desired plane and suspend the bag therefrom, as will now be described.

The joint member comprises two channel shaped pieces 14—15 of which 14 is the larger 40 and 15 fits longitudinally within and between the flanges of 14 with its flanges directed inward toward the web of member 14, each channel having a central bore for insertion of a screw 16 with a thumb-nut 16N. By means of this screw and 45 nut the lower ends of the handle are rigidly but removably clamped and retained between the channels, in the upper half thereof (see Figs. 2, 3, 4 and 6).

Between the lower adjacent extremities of the 50 joint channels the finger ends of the loop 12 are clamped and retained in any one of three selective positions to hold the loop and the bag opening in corresponding positions.

At the lower end of channel 15 its web is cut 55

out in inverted U-shape, as 15B, and both channels are provided in their respective flanges with pairs of registering shallow grooves 19 in and between which the respective end parts of loop 12 adjacent fingers 12A are pivotally but removably clamped. Assuming that the fingers 12A are positioned within the joint directed upwardly (as in Fig. 7) the loop will of course be positioned rigidly extending downwardly from the joint and handle in a plane common thereto.

If the fingers 12A are directed outward in the cut-out 15B (as in Figs. 1, 2 and 3) the loop 12 is rigidly retained in a plane at right angles to the handle and the bag is thus suspended with its opening in corresponding plane and the interior of the bag easily accessible for taking out or putting in clothespins.

The handle has a two point contact on a clothesline and the bag is suspended quite rigidly in non-rotatable position.

When the loop 12 is in the open horizontal position as in Fig. 2 it may be swung upwardly to and against the handle 10 as to the dotted line position thus making the entire device, including the bag, occupy a minimum of space for stacking, boxing and shipping purposes. It will be readily understood that when the device is unpacked from said compact condition and the loop is sprung out to right angle position the fingers 12A are sprung upwardly and toward each other in the cutout 15B of the joint channel member 15 and become seated in the bottom of said cut-out (best shown in Fig. 3).

The loop 12 may of course be entirely removed from the joint member by necessary simple manipulation of the thumb-nut to loosen and allow the channel members to be spread at their lower ends, such spreading at the lower parts being necessary to release the bearing contact and pivotal action on the loop. It is not necessary to remove the loop ends or even to release the thumb nut in order to swing the loop member into or out of either of the two positions shown in Fig. 2, but to position the loop in a common plane with the handle and below the joint the channel members must be loosened and spread sufficient to permit the loop fingers 12A to be

directed upwardly between the joint channel members 14—15 and subsequently clamped between them, as is distinctly illustrated in Fig. 7.

I have herein described and illustrated in the accompanying drawing the preferred construction of my device but it is obvious that modifications thereof may be embodied without departing from the scope and spirit of my invention.

I claim:

1. In a bag holder of the class described having an elongated upright wire handle the lower end of which comprises a pair of parallel wires, a bag suspended from the lower part of said handle, said bag having a hemmed opening; an open wire ring removably retained in said hem and its adjacent ends protruding therefrom, a joint device at the lower end of the handle comprising a pair of registering metal channel pieces, a bolt traversing the center part of said joint to clamp the handle wires therebetween at and over the bolt, said ring formed at each of its ends with a right angled terminus, both in close parallel relation, and means in said joint channels, below the bolt, to positively engage said ring termini in either of two selective positions.

2. The structure specified in claim 1 in which said channels are positioned with their flanges in guiding contact, the ring engaging means thereof comprising the provision of a pair of registering notches in each pair of close flanges to removably engage the ring member adjacent its angular termini.

3. The structure specified in claim 1, in which said channels are positioned with their flanges in guiding contact, the ring engaging means thereof comprising the provision of a pair of registering notches in each pair of contacting flanges, to removably engage the ring member adjacent its angular termini, said ring termini extending in the plane of the ring and positioned between the webs of said channels when the ring is positioned parallel to the handle, one of the channel web parts having a downward cutout proportioned to allow the ring ends to be swung up and the ring out to a bag suspending position, as shown and described.

CARL S. HEDQUIST.
